CLAIM

The ornamental design for a jug, as shown and described.

DESCRIPTION

FIG. 1 is a top front perspective view of a jug showing my new design;

FIG. 2 is a right side view thereof;

FIG. 3 is a rear view thereof;

FIG. 4 is a front view thereof;

FIG. 5 is a left side view thereof;

FIG. 6 is a top elevational view thereof;

FIG. 7 is a bottom elevational view thereof; and,

FIG. 8 is an exploded perspective view thereof.

The broken lines in the drawings depict portions of the jug that form no part of the claimed design.
